(No Model.)

W. H. STARRY.
SWINGING GATE.

No. 330,937.

Patented Nov. 24, 1885.

UNITED STATES PATENT OFFICE.

WILLIAM H. STARRY, OF TRENTON, OHIO.

SWINGING GATE.

SPECIFICATION forming part of Letters Patent No. 330,937, dated November 24, 1885.

Application filed February 5, 1885. Serial No. 154,997. (No model.)

To all whom it may concern:

Be it known that I, WILLIAM H. STARRY, a citizen of the United States, residing at Trenton, in the county of Butler and State of Ohio, have invented certain new and useful Improvements in Swinging Gates; and I do hereby declare that the following is a full, clear, and exact description of the same, reference being had to the annexed drawings, making a part of this specification, and to the letters and figures of reference marked thereon.

Figure 1 of the drawings is a front elevation of a swinging gate embodying my invention; Fig. 2, a top plan view of the bracket and its connections for supporting and operating the rear end of the gate; Fig. 3, an under plan view thereof; Fig. 4, a longitudinal central section taken on line xx of Fig. 2; Fig. 5, a perspective view of the tripping device over which the rim of the vehicle-wheel passes to operate the gate; and Fig. 6, a detail view of the take-up for shortening or lengthening the connecting-rod.

The present invention has relation to that class of swinging gates operated by the contact of the rim of the vehicle-wheel with a tripping device connecting the gate with a lever-rod.

The object of the present invention is to improve the construction of the mechanism heretofore employed for operating the gate, whereby the usual counterbalance and double-crank rods are dispensed with and a more perfect action of the operating mechanism obtained. These objects I attain by the construction substantially as shown in the drawings, and hereinafter described and claimed.

In the accompanying drawings, A represents the gate, provided with brace-rods a , said gate being hinged to the post B, and retained closed by a latch, b , engaging with a keeper, c , on post C. The rear batten, d , of the gate, at the upper end thereof, is connected to the post B by the usual hinge, as shown at e , and to the lower end of the batten is bolted the pivot-arm f . The lower end of the arm f is formed cylindrical, and extends down through an elongated opening, g , in the horizontal portion of a bracket, D, secured to the post B. The pivot-arm f is provided with a collar, h , and between this collar and the bracket are placed levers E, the inner ends

fitting loosely over the pivot-arm and bearing against fulcrum-blocks i on the bracket, while the outer ends of the levers are supported by flanges k . The lower end of the bolt f passes through an elongated opening, l , in a plate, F, pivoted at its outer end to the under side of the bracket D. A curved spring, G, bears against the under side of the plate F, its free end working in a groove or mortise, m , in the plate, to return the plate to its normal position when closing the gate. The plate F, which I term "a locking-plate," is disengaged from pivoted dogs n by being depressed, as shown in dotted lines, Fig. 4, thus allowing the plate to be carried along with the pivot-arm f when moving in the slot g in opening the gate. This depression of the plate F is caused by the action of the beveled end of a tongue, o , projecting from the pivot-arm f , acting on the correspondingly beveled face of a lug, p , upon the locking-plate when the pivot-arm moves forward in the slot l .

To the ends of the levers E are connected one end of rods H, which are screw-threaded to engage with screw-threaded holes in blocks I, thus providing a take-up for the rods to adjust them to cold and heat, or compensate for contraction and expansion, by lengthening or shortening the rods from the point of attachment at their extremities. The blocks I are pivoted to the under side of the levers E, so that the latter will freely operate by means of their swivel-connection with the rods. The opposite ends of the rods H are connected to trip-levers J, one upon each side of the gate. The lever J is pivoted to a support, r , which is bolted to a base, K, sunk into the ground, so that its upper edge will be flush therewith. The pivoted trip-lever J is formed with a curved elbow, s , and terminates in a double incline, $t u$, at its free end, over which travels a friction-roller, w , upon a crank, L, pivoted to the sides of the base K. The normal position of the trip-lever and its connections when the gate is closed is shown in full lines, Fig. 5. When a vehicle passes in the direction of the arrow, the rim of the wheel will depress the pivoted crank L as it passes over it. This action upon the crank L will cause it and the friction-roller w to pass over the curved shoulder s of the lever J, as shown in dotted lines, a space, y , being provided at the

side of the base K to allow the lever to enter when depressed by the action of the crank and friction-roller. As the trip-lever J is depressed by the means above stated it will draw on the 5 rod H to which it is connected, and bring the levers E on a line with the rods, as shown in dotted lines, Fig. 2. When the levers E are thus acted upon, they are pressed against the blocks i, which act as fulcrums, causing the 10 pivot-arm f to move forward in the slots g and l, which raises the front end of the gate and unlatches it. At the same time that the pivot-arm f moves forward in the slots g l the tongue o, acting against the lug p, depresses the locking-plate F, thereby releasing it from the dogs n, which allows the pivot-arm to move transversely in the slot g, carrying with it the locking-plate, and throwing the gate out of balance 15 to open in an opposite direction to the tripping device over which the vehicle-wheel has passed. The trip-lever and its connections at the opposite side of the gate still remain in their normal position until acted upon by the 20 passing vehicle-wheel, when that trip-lever is in like manner depressed, bringing the pivot-arm f back to position, carrying the plate F with it, so that the plate will be in line with the pivoted dogs n, when the spring G will 25 press the plate upward into engagement therewith to hold it stationary and lock it in position, thus causing the gate to swing to its closed position.

Having now fully described my invention, what I claim as new, and desire to secure by 30 Letters Patent, is—

1. In a swinging gate, the combination, with a tripping device composed of a pivoted lever having a curved elbow and incline, of a hinged connection for the gate, consisting of a 35 bracket, a locking-plate pivoted thereto, a pivot-arm connected to the gate and supported in the bracket, and levers for operating said arm and plate, substantially as and for the purpose set forth.
2. In a swinging gate, the combination, with a tripping device, of a hinged connection for the gate, consisting of a bracket provided upon its under side with a locking-plate pivoted thereto, a spring for automatically pressing 40 the plate into engagement with dogs upon the bracket, a pivot-arm secured to the gate and supported in the bracket, levers for operating said arm and locking-plate, and fulcrum-blocks upon the upper side of the bracket for

the levers, substantially as and for the purpose 55 specified.

3. In a swinging gate, the combination, with a tripping device, of a hinged connection for the gate, consisting of a bracket provided with a pivoted locking-plate, having a beveled face 60 lug and a slot, and a pivot-arm operated by levers, and provided with a tongue having a beveled end to act against the face of the lug, substantially as and for the purpose described.

4. In a swinging gate, the combination, with 65 a tripping device, of a hinged connection for the gate, consisting of a bracket, a pivoted arm supported thereby, levers for operating the arm, blocks to form fulcrums for the levers, a pivoted locking-plate, and a spring to act on 70 the plate, substantially as and for the purpose set forth.

5. A hinged connection for an automatically-operating gate, consisting of a pivot-arm connected to the gate, having a beveled 75 tongue, and levers for operating the arm, in combination with a bracket having a slot or opening, fulcrum-blocks for the levers, and a pivoted and slotted locking-plate provided 80 with a beveled lug, and a spring for pressing the plate upward in engagement with dogs upon the bracket, substantially as and for the purpose specified.

6. A tripping device for automatically- 85 swinging gates, consisting of a pivoted trip-lever having a curved elbow and double incline, as shown, in combination with a pivoted crank for operating the lever, substantially as and for the purpose described.

7. In a swinging gate, a hinged support for 90 connecting the same to the gate-post, consisting of a bracket, a pivot-arm, and pivoted locking-plate, in combination with levers for operating the pivot-arm, having at their free ends pivoted blocks, and rods connected there- 95 to and to pivoted trip-levers formed with curved elbows and double inclines, and pivoted cranks for operating the same, substantially as and for the purpose set forth.

In testimony that I claim the above I have 100 hereunto subscribed my name in the presence of two witnesses.

WILLIAM H. STARRY.
